UNITED STATES PATENT OFFICE.

WILLIAM RATCLIFF AND HUGH WALLACE, OF LONDON, ENGLAND, ASSIGNEES TO THE VICTORY-KIDDER PRINTING MACHINE COMPANY LIMITED, OF BIRKENHEAD, ENGLAND, A COMPANY OF GREAT BRITAIN.

PRINTING MACHINE.

Application filed August 27, 1921. Serial No. 496,168.

To all whom it may concern:

Be it known that we, WILLIAM RATCLIFF, a subject of the King of Great Britain, and a resident of 75 Tulse Hill, London, S. W. 2, 5 England, and HUGH WALLACE, a subject of the King of Great Britain, and a resident of 18 Somerfield Road, Finsbury Park, London, N. 4, England, have invented a new or Improved Printing Machine, of which the 10 following is the specification.

The object of this invention is to provide a printing machine of great simplicity, compactness and cheapness of manufacture, and of a greatly reduced weight and size as compared with lithographic printing machines 15 hitherto known.

The flat bed machine as hitherto widely used occupies at least twice the space of the machine according to the present invention 20 and the weight is at least twice as much and the work done by it is we claim only about half as much in a given time.

The hitherto known rotary machine which 25 comprises a continuously rotating cylinder, is not made to do short runs on account of the difficulty and trouble and time involved for the inking process and the like, and in this machine the damping arrangement is not as satisfactory as on the flat bed machine hitherto used. In the known rotary 30 machine also the making ready from one colour to another takes some hours and wastes a great deal of ink. The machine according to the present invention possesses 35 the advantage of the known rotary and flat bed machines without the foregoing disadvantages of either of them.

According to the present invention we 40 provide a cylinder mounted on a shaft and adapted to oscillate thereon or make a partial rotation, and the cylinder is provided with a printing surface, an inking slab, and a damping surface, arranged at suitable angles apart thereon, and each adapted to 45 come into contact with its required co-operating element during a portion of its oscillation.

The cylinder is provided with a toothed 50 wheel secured upon the same shaft adapted to gear with a quadrant or curved rack which is caused to operate by means of a link and gear wheels as afterward described, to provide the required movement of oscillation or partial rotation of the said cylinder.

der and thereby bring into operative position for engagement in succession the necessary co-operative elements for printing. 55

Further details of construction and improved mechanism of the said machine to effect the operation of our novel method and arrangement will be apparent by a reference to the drawings attached hereto which illustrate the preferred mode of carrying our invention into effect. 60

Fig. 1 is an end elevation of the machine 65 according to our invention.

Fig. 2 is a front elevation of the machine.

Fig. 3 is a separate view of the cylinder and its operating mechanism without the 70 frame.

Fig. 4 is a front view of the cylinder and its operating mechanism.

Fig. 5 is a section of the cylinder.

Fig. 6 is a fragmental view illustrating 75 the connection between one of the driven gears and the blanket cylinder; and,

Fig. 7 is a view taken at right angles 80 thereto.

A is the oscillating cylinder secured to the shaft A¹ which is mounted in bearings fitted in the frame plates B, B¹. Secured on the shaft A¹ is the gear wheel A² which meshes with the teeth of the quadrant or rack C. The quadrant C forms part of a bell crank lever D fulcrumed at D¹, the 85 lower arm D² of which lever has connected thereto the link E which is fitted to the crank pin E¹, rigidly secured to the gear wheels E², E³, one of which is mounted on a pin and the other on the shaft E⁴, fitted in 90 bearings in the frame plates. The gear wheels E², E³, are driven by the pinion E⁵ which is mounted on the parallel shaft E⁶. The shaft E⁶ has also mounted thereon the pulleys E⁷ by which the machine is driven. 95

The cylinders F and G are mounted on shafts F² and G² respectively fitted in adjustable bearings as shown, Fig. 1, secured in the frame plates B and B¹. The cylinder F is adapted to engage the cylinder A during its oscillation or rotation in one direction only in a similar manner to that in a flat bed litho machine. 100

The shaft F² carrying the cylinder F has loosely mounted thereon a gear wheel F¹ 105 which meshes with the gear wheel A³ fixedly secured to the shaft A¹, and the gear wheel G¹ which is loosely mounted upon the

- shaft G^2 also meshes with the gear F^1 whereby upon the oscillation of the shaft A^1 , the gears F^1 and G^1 will oscillate therewith, but will not move the shafts F^2 and G^2 as they are loosely mounted thereupon. The gear wheel A^4 also secured to the shaft A^1 is adapted to mesh with a segmental gear F^4 fixed to the shaft F^2 , and this gear F^4 meshes with the gear G^4 .
- 10 Pivottally mounted upon a pin S secured in a suitably formed boss on the gear wheel F^1 is a pawl R (see Figs. 3, 6 and 7) provided with lateral projections R^1 and R^2 . The projection R^1 is adapted to travel in 15 a guiding slot S^1 in the flange of the wheel F^1 , while the projection R^2 of the pawl R is adapted to engage the diametric face of a tapered lug or projection T secured to the outer face of one end plate of the segmental blanket cylinder F . From this, it 20 is obvious that when the gear wheel F^1 is moved in a clockwise direction, the pawl projection R^2 will abut against the lug T and the cylinder F will be caused to move therewith or rotated in a clockwise direction. As the gear F^1 oscillates, the pawl R will not engage the lug T when the gear moves in anti-clockwise direction, and therefore, this connection between the oscillating gear F^1 and the cylinder F will cause the latter to move in one direction only. When the gear A^4 moves in an anti-clockwise direction, the blank portion of the segmental gear F^4 registers with the gear A^4 , 30 and the pawl R carried by the gear F^1 moves away from the projection T ; thus, no movement will be transmitted to the cylinder F . After one complete revolution in this anti-clockwise direction, the pawl R after being lifted by the camber of the projection T falls into place behind it and on the gear F^1 , changing its direction and again moving the cylinder forward until the teeth of the gear F^4 mesh with the gear 40 A^4 , which will cause the cylinder G to move also in one direction as the gear G^4 meshes with the gear F^4 .
- The object of the duplicated gear wheels on either end of the shafts A^1 and F^2 is 50 that, during the actual process of printing, that is, when the rubber blanket of the cylinder F engages and is in contact with the type or printing surface H of the cylinder A , the maximum torsional power is required to be transmitted to the cylinder gears F^4 and A^4 , not through the medium of the pawl R , although this is still engaged. In the absence of these gear wheels, this pawl would be called upon to take the whole 55 strain. In this connection, it is pointed out that when the pawl R alone moves the cylinder forward, the surfaces of the cylinders F and A are not in contact, and therefore, apart from bearing friction, there is little 60 resistance to motion.

When it is desired to run the machine "light" and to cease the printing process, the cam lever V mounted on the shaft O is lifted into engagement with the pawl R , in such manner that the said pawl will ride on the cam lever after engaging the camber of the lug T and will thus be prevented from dropping into engagement with the driving face of the said lug. No engagement will then be effected between the gear wheel F^1 70 and the cylinder F , and the gear wheel F^4 being, in this position, out of engagement with the right hand spur wheel A^4 , the cylinder F will remain stationary during both directions of rotation of the gears A^3 80 and F^1 . A hand lever Q is provided for operating the cam lever V .

The cylinder A is formed of segments mounted in two discs one at each end.

The cylinder F is provided with a rubber 85 blanket which as it revolves in contact with the cylinder A , when moving in one direction takes the print off the printing surface H to which part is secured the plate having the printing matter on it, the surface H forming a segment of the cylinder A , (see Fig. 5). The cylinder G carries the paper and presses it on to the blanket on the cylinder F . I is the slab which carries ink to the rollers I^1 . The rollers I^1 roll over and distribute ink to the printing plate on the segment H . The rollers K distribute ink evenly on the inking slab I . The segment L (see Figs. 1 and 5) forms a damping board which damps the rollers L^1 and the rollers L^1 damp the plate on the printing segment H during the oscillation of the cylinder A . From the support J the paper is fed from boards to the cylinder G for printing. 90

Referring to Fig. 1, M is a receptacle for ink which supplies the roller M^1 . The roller M^1 conveys its ink to the roller M^2 in contact therewith. The cam boss N on the shaft E^4 during its rotation moves the lever N^1 and thereby by the link N^2 operates the bellcrank lever M^3 by the medium of the bellcrank lever N^3 . This movement brings the roller M^2 into contact with the inking slab I when the slab I is brought by the rotation 100 of the cylinder A opposite the roller M^2 to feed ink thereto.

With regard to the process of operation of the oscillating cylinder A carrying the type or printing surface H , the ink slab I , and the damping board L , let it be assumed that the operation commences from the position of maximum oscillation to the left or in an anti-clockwise direction. In this position, the printing surface H has passed under the damping rollers L^1 once; the inking surface I has distributed ink to the inking rollers I^1 , having first taken ink from the roller M^2 and had the said ink evenly distributed over its surface by the rollers K . 110

The segmental cylinder F carrying the rubber blanket partially round its circumference is at its point of maximum rotation. The pawl R mounted on the wheel F¹ is about to move away from the projection T secured to the cylinder F and the blanket or toothless segment of the gear wheel F⁴ is presented to the teeth of the right hand wheel A⁴. The circumferentially arranged 10 segment forming the rubber blanket of the cylinder is in its uppermost position and there is thus no point of contact between the cylinders A and F, neither are they operationally connected.

15 The cylinder A now rotates to the right in a clockwise direction, the type or printing plate H passes again under the damping rollers L¹ which damp the printing surface, and then under the inking rollers I¹ obtaining ink therefrom. The ink slab I moves round until it engages the ink roller M² from which it obtains a fresh supply of ink; the damping board L passes under the damping rollers L¹ and moistens the surface 20 thereof. During this process as before stated, the cylinders F and G remain stationary.

The direction of rotation now changes. The loosely mounted gear wheel F¹ having been given a complete revolution, the pawl R again drops into engagement with the lug T and on the cylinder A, commencing to rotate to the left, the said pawl moves the cylinder F in a clockwise direction, causing 30 the teeth of the gear wheel F⁴ to once again move into engagement with the teeth of the gear wheel A⁴ and the cylinders F and G are rotated thereby. The printing plate now moves forward again passing under the ink rollers I¹, and contacting with the blanket of the cylinder F transfers an imprint from its surface to the said blanket, which in turn, transfers the said imprint to the paper which passes between the cylinder G and the said blanket.

45 The cylinder A now moves to its maximum position of left hand rotation under the damping rollers L¹ and the cylinders F and G having been given a complete rotation are then disengaged from the driving gears in the manner before described and remain stationary. The cycle is then ready to be repeated.

50 The other parts shown on the figures are of the usual kind employed in other printing machines, they do not constitute part of this invention and are not therefore referred to.

55 In comparison with both the slab bed machine and the usual rotary machines it will be obvious that not only is this machine much simpler having far fewer working parts and being correspondingly cheaper to manufacture but the power required to operate the machine according to the present

invention will be very considerably less than either of the said known machines.

Our method and construction also by dispensing with a large number of rollers as employed in the rotary machines and other parts and appliances necessary to move the parts out of contact with the rotating cylinder in succession, not only provides a cheaper, simpler and lighter machine but also reduces the power required to drive it.

60 What we do claim as our invention and desire to secure by Letters Patent is:—

1. In a machine of the class described, a shaft, a cylinder mounted upon the shaft, means to oscillate said cylinder, said cylinder being provided with segmental portions spaced about the cylinder and constituting respectively a printing plate, a damping surface, and an inking surface, a transfer roller, means operable through the oscillation of the cylinder to actuate said transfer roller in a step by step movement of rotation in one direction, and an impression roller against which the transfer roller bears.

65 2. In a machine of the class described, a shaft, a cylinder mounted upon the shaft, a gear fixed on said shaft, a segmental gear meshing with the first mentioned gear, a rotary crank having a radius less than the radius of the segmental gear, a link connecting the segmental gear to the rotary crank, said cylinder being provided with segmental portions spaced about the cylinder and constituting respectively a printing plate, a damping surface, and an inking surface, a transfer roller, means operable through the oscillation of the cylinder to actuate said transfer roller in a step by step movement of rotation in one direction, and an impression roller against which the transfer roller bears.

70 3. In a machine of the class described, a shaft, a cylinder mounted upon the shaft, a gear fixed on said shaft, a segmental gear meshing with the first mentioned gear, a rotary crank having a radius less than the radius of the segmental gear, a link connecting the segmental gear to the rotary crank, said cylinder being provided with segmental portions spaced about the cylinder and constituting respectively a printing plate, a damping surface, and an inking surface, a transfer roller, means operable through the oscillation of the cylinder to actuate said transfer roller in a step by step movement of rotation in one direction, and an impression roller against which the transfer roller bears.

75 4. An improved lithographic printing machine comprising a main cylinder having

ing damping, inking, and printing surfaces arranged thereupon, a blanket cylinder, means for transmitting an oscillating movement to said main cylinder, and means whereby upon the oscillation of said main cylinder said blanket cylinder will be caused to rotate in one direction.

5. An improved lithographic printing machine comprising a main cylinder, the 10 periphery of said main cylinder being divided into damping, inking and printing surfaces, means for transmitting an oscillating movement to said main cylinder, a blanket cylinder arranged above said main 15 cylinder, an impression cylinder, and means operatively connecting said blanket and impression cylinder with said main cylinder whereby said blanket and impressions cylinders will be caused to intermittently move 20 in one direction, substantially as and for the purpose specified.

6. A lithographic printing machine comprising a frame, a drive shaft mounted within said frame, a driven shaft mounted within said frame and above said drive 25 shaft, means for operatively connecting said driven shaft with said driving shaft whereby said driven shaft may oscillate, a cylinder carried by said driven shaft, said cylinder being provided with damping, inking and printing surfaces, a blanket and impression cylinder supported within said frame and arranged above said main cylinder, means for operatively connecting said impression and blanket cylinder with said 30 main cylinder, inking, and damping rollers supported within said frame and adapted to contact with the inking, damping and printing surfaces of said main roller.

WILLIAM RATCLIFF.
HUGH WALLACE.
